UNITED STATES PATENT OFFICE.

ELI R. MANOR, OF ST. PAUL, MINNESOTA.

FIRE ARCH FOR LOCOMOTIVE BOILERS.

Application filed June 18, 1924. Serial No. 720,786.

To all whom it may concern:

Be it known that I, ELI R. MANOR, a citizen of the United States, residing at St. Paul, in the county of Ramsey and State of Minnesota, have invented certain new and useful Improvements in Fire Arches for Locomotive Boilers; and I do hereby declare the following to be a full, clear, and exact description of the invention, such as will enable others skilled in the art to which it appertains to make and use the same.

My invention provides an extremely simple and highly efficient air-ventilated fire arch for locomotive boilers, and, generally stated, the invention consists of the novel construction, combinations and arrangement of parts hereinafter described and defined in the claim.

Hitherto, it has been the commercial practice in locomotive boilers to provide arch tubes and to support the arch blocks on these arch tubes. In some instances, the arch blocks have been provided with air passages and the air has been supplied thereto by indirect means, such as supply tubes extended from points remote from the arch. In accordance with my invention, the air is supplied to the air passages of the blocks directly through the side plates of the fire box and the air thus drawn in through the fire blocks or tiles of the arch will be superheated and delivered into the combustion chamber of the fire box, thereby intensifying the combustion and producing more rapid initial combustion with the resulting greater economy in the use of fuel and elimination of the smoke nuisance.

In the accompanying drawings, which illustrate the invention, like characters indicate like parts throughout the several views.

Referring to the drawings:

Fig. 1 is a fragmentary vertical section taken from front to rear through the fire box of the locomotive substantially on the line 1—1 of Fig. 2;

Fig. 2 is a transverse section taken on the line 2—2 of Fig. 1;

Figs. 3 and 4 are perspective views showing in detail certain of the arch blocks or tiles illustrated in Figs. 1 and 2;

Fig. 5 is a transverse section on the line 5—5 of Fig. 1;

Fig. 6 is a plan view showing a portion of the arch, some parts being broken away;

Fig. 7 is a fragmentary vertical section on the line 7—7 of Fig. 6;

Fig. 8 is a view corresponding to Fig. 5, but illustrating a slightly modified form of the blocks; and

Fig. 9 is a view corresponding to Fig. 7, but illustrating a further modified form of the arch blocks.

The numerals 10 and 11 indicate, respectively, the shell of the fire box and the surrounding boiler shell, which parts are of the customary well known arrangement, spaced to form a water space 12 that surrounds and overlies the fire box. The numeral 13 indicates the customary fuel supply passage normally closed by the customary door, not shown. The numeral 14 indicates the arch flues that extend from rear to front through the combustion chamber, are forwardly inclined, and connect the front and rear portions of the water space or leg 12. The numerals 15 indicate clean-out plugs applied to the boiler shell 11 in line with the ends of the arch tubes 14. This is the customary arrangement of arch tubes and, as already stated, such arch tubes have hitherto been used to support arch-forming blocks or tiles.

Preferably, the arch is made up of highly refractory blocks or tiles 16 and 17 of the form illustrated in Figs. 1, 2, 3, 4, 5, 6 and 7. The blocks 16, at the under sides of their end portions, are formed with segmental notches 16^a that fit and rest upon the arch tubes 14, and the blocks 17 that are at the sides of the arch are provided at their inner ends with similar segmental notches that also fit and rest upon the arch tubes. At their outer ends, the side blocks 17 are formed with recesses that adapt them to be telescoped onto the inwardly projecting ends of short air intake tubes 18 that extend directly through the sides of the outer shell 11 and fire box 10. These air intake tubes 18 are flanged and expanded in the sides of the shells 10 and 11, so that fluid-tight joints are formed and the inwardly projecting ends thereof afford supports for the outer ends of the said blocks 17. Preferably, the said air tubes 18 are of highly refractory steel or other suitable metal. If desired, the sides of the fire box sheet 10 may be provided with ledges 19, underlying and assisting in supporting the outer ends of the blocks 17.

In line with the air intake tubes 18, the blocks 17 and 16 are provided with longitudinal air passages 20. These air passages 20 of the blocks that are in transverse

alignment register with each other, so that they form a complete transverse air passage. The arch blocks illustrated in Figs. 1, 2, 4, 5, 6 and 7, at their abutting ends, 5 are formed with interlapping tongue and groove joints at 21 that hold the blocks against shifting movements forwardly and rearwardly of the arch, but the block shown in Fig. 1 has a simple flat end. Both types 10 of blocks just noted, however, are provided with relatively small air discharge passages 22 that lead upwardly to the tops of the blocks from the main air passages 20 and deliver air to the top of the arch. In the 15 form of the arch shown in Fig. 8, the blocks are further provided with small air passages 23 that lead downwardly to the lower surfaces of the blocks from the said main passages 20. The blocks illustrated in 20 Fig. 9 are shown as formed with both vertically and obliquely extended upper and lower air discharge passages 22^a and 23^a.

In the construction illustrated in Figs. 1, 2, 3, 4, 5, 6 and 7, the arch blocks 16 and 25 17 that are at the inner edge of the arch are further provided with small forwardly extended air discharge passages 24 that lead from the main air passages 20 and discharge air into the flames where they make 30 their turn around or from the lower to the upper portion of the arch and, hence, intensify the combustion at this turning point and, moreover, assist in keeping down the 35 temperature of the blocks at the place where the flames lap around the blocks and would otherwise have maximum fusing action on the blocks.

The blocks at the front edge of the arch, 40 adjacent to the low front wall of the fire box, may be and, as shown, are slightly spaced from the said fire box by laterally spaced relatively small spacing blocks or fire tiles 25 placed on the lower ends of the arch tubes 14, as shown in Figs. 1 and 6. 45 This arrangement permits passage of some of the flames directly through the front and lower portion of the arch.

In assembling the blocks of the arch, the blocks 17 should first be telescoped onto the 50 projecting ends of the air intake tubes 18 and rested on the outer arch tubes 14 and then the intermediate blocks may be readily dropped into position. The air intake tubes are thus not only utilized to at least 55 in part support the blocks 17, but they hold the said blocks against shifting movements forwardly and rearwardly and insure the main air passages 20 always being in line with the air intake passages through the 60 sides of the fire box.

Of course, the fire blocks will become very

hot in the operation of the locomotive, so that air drawn in by suction or partial vacuum will be heated to high temperature before being discharged into the flames and 65 this, of course, produces rapid initial combustion with a resulting high temperature in the fire box and flues. Some kinds of fuel will be burned with the greatest efficiency when the air is delivered directly 70 into the combustion space above the arch, but other kinds of fuel will burn with the greatest kind of efficiency when the air is discharged both above and below the arch. For example, in the use of high combustion 75 fuel, such as coal, that burns rapidly and with a quick flash, it is better to introduce the superheated air at the upper rather than at the lower portion of the arch, for the reason that introduction of the hot air 80 below the arch would tend to rapidly hasten the combustion and cause the flames to flash from the fuel door when opened. In certain slower burning coals or fuels, the introduction of the superheated air both above 85 and below the arch will give the best results. However, these are conditions best determined by experiment. The vertical and oblique arrangement of air passages shown in Fig. 9 gives a more complete and better 90 distribution of the superheated air, but the more simple arrangements illustrated will properly meet most conditions. By interlocking the ends of the blocks as best shown in Fig. 6, the blocks of the arch are interconnected so that they cannot shift out of 95 relative positions, even if some of the spacing blocks 25 or other blocks of the arch should give away.

What I claim is:

A boiler of the locomotive type provided with arch tubes extended through the fire box thereof from the surrounding water space, in combination with arch-forming blocks supported on said arch tubes with 105 their ends abutting above said tubes and provided with aligned air passages extended transversely through the arch and delivering into the combustion chamber, and intake tubes extended directly through the sides 110 of the boiler and projecting into the aligned air passages and assisting and supporting adjacent blocks, said air intake tubes being provided on both sides of the fire box, each transverse row of arch forming blocks 115 having the transverse air passages noted, and there being one air intake tube injected into each end of each of the transverse air passages of the arch formed by said blocks.

In testimony whereof I affix my signature,

ELI R. MANOR.
